(57) **CLAIM**

The ornamental design for an oven mitt, as shown and described.

DESCRIPTION

FIG. 1 is a top plan view of a first embodiment of the oven mitt of my new design, the bottom plan view is the mirror image thereof;

FIG. 2 is a left side elevation view thereof;

FIG. 3 is a right side elevation view thereof;

FIG. 4 is a rear elevation view thereof;

FIG. 5 is a front elevation view thereof; and,

FIG. 6 is a top plan view of a second embodiment of the oven mitt; the bottom plan view is the mirror image thereof; the right and left side elevation view and the front and rear elevation views are the same as FIGS. 2, 3, 4 and 5 respectively.

The broken lines showing of the cuff, ring and tab are for illustrative purposes only and forms no part of the claimed design.

The broken lines shown on the second embodiment are understood to represent stitching.
